Specification for Design.

Patented Apr. 14, 1914.

Application filed June 24, 1912. Serial No. 705,665. Term of patent 14 years.

To all whom it may concern:

Be it known that I, GARDNER E. WHEELER, a citizen of the United States, residing in New Haven, county of New Haven, and State of Connecticut, have invented a new, original, and ornamental Design for an Automobile Radiator-Casing, of which the following is a specification when taken in connection with the accompanying drawing.

In the drawing, Figure 1 is a perspective view of an automobile radiator casing em-

bodying my design; Fig. 2 is a side elevation of the casing; and Fig. 3 is a top plan view of the same.

What I claim is:—

The ornamental design for an automobile radiator casing, substantially as shown.
